UNITED STATES PATENT OFFICE.

FRANK SALVATO, OF BOSTON, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-SEWING MACHINE.

1,202,899.

Specification of Letters Patent.

Patented Oct. 31, 1916.

Application filed May 12, 1915. Serial No. 27,668.

To all whom it may concern:

Be it known that I, FRANK SALVATO, a subject of the King of Italy, and resident of Boston, county of Suffolk, State of Massachusetts, have invented an Improvement in 5 Buttonhole-Sewing Machines, of which the following description, in connection with the accompanying drawing, is a specification, like characters on the drawing representing like parts.

This invention relates to buttonhole sewing machines and has for its object to provide a novel sewing machine of this type to produce a buttonhole having a purl effect 15 on the upper face of the goods as well as on the under face on which the loops of thread are interlocked with each other. I secure this end herein by providing means for concatenating a purl thread with the portions 20 of the needle thread that are exposed on the upper face of the goods, said purl thread being twisted about the portions of the needle thread that connect the successive loops. This result is secured by means of 25 a vibrating purl thread guide which co-operates with the needle to lay the purl thread during the formation of each stitch in such a position that when the needle is given its penetrating thrust it will lay the needle 30 thread over the purl thread, said purl thread guide operating between successive needle thrusts to carry the purl thread over the needle thread.

My invention is applicable to buttonhole 35 sewing machines of various types.

In order to give an understanding of my invention I have illustrated it herein as it might be applied to a buttonhole sewing machine of the "Reece" type, such, for instance, as is shown in United States Patent 40 No. 862,238, dated August 6, 1907, but I wish to state that the invention is capable of being applied to other buttonhole sewing machines.

In the accompanying drawings, Figure 1 is a side view of a buttonhole sewing machine having a construction similar to that illustrated in the above-mentioned United States Patent No. 862,238, and having my 50 improvements applied thereto; Fig. 2 is a view showing the needle and purl thread guide in front elevation and showing the lower portion of the head of the sewing machine in section; Fig. 3 is a sectional view on the line $x-x$, Fig. 4; Fig. 4 is a section

on the line $y-y$, Fig. 2; Fig. 5 is a section on the line $a-a$, Fig. 4; Fig. 6 is a front view of the looper mechanism which cooperates with the needle in forming the stitch; Figs. 7 and 8 are enlarged diagrammatic views showing the character of the stitch formed with the sewing machine and the steps in the operation thereof.

The sewing machine herein illustrated is of that type in which the buttonhole stitch 60 is formed from a single needle thread by means of the usual reciprocating needle situated above the work and looper mechanism below the work, said looper mechanism 65 co-operating with the needle to take each loop of needle thread and position it so that upon the next penetrating thrust the needle will pass therethrough thereby enjoining or concatenating the successive loops of needle 70 thread with each other.

Inasmuch as the main features of the sewing machine herein illustrated are similar to that shown and described in the above-mentioned United States Patent No. 862,238, it will not be necessary to enter into a detailed description of the machine as the following summarized brief description thereof when taken with the above-mentioned 80 patent will suffice to give to anyone skilled in the art an understanding of the invention.

The needle 1 of the sewing machine is sustained by the usual needle bar 2 which is mounted for reciprocation in the head portion 3 of the frame 4. This needle bar 90 not only has a vertical reciprocating motion, but also has a lateral movement so that upon one thrust of the needle it will pass from one side to the other of the goods 95 at the edge of the buttonhole and at the next thrust will pass through the goods at a distance back from the edge of the buttonhole equal to the length of the depth stitch, as set forth in said patent. To permit of this the needle bar reciprocates through a ball-and-socket bearing 5 situated at the upper end of the head 3 which permits of a lateral swinging movement thereof, said needle bar passing through a bearing member 6 sustained on the underside of the head 3, as will be presently described, and which has a vibrating movement in timed relation 100 with the stitch-forming operation. The needle bar is given its vertical reciprocation through a lever 7 pivoted to the frame 4 at 105 the line $x-x$, Fig. 4; Fig. 4 is a section

8 and actuated by an eccentric 9 which has rigid therewith a gear 10 that meshes with a gear 11 on the driving shaft 12, the latter being operated from any suitable source of power. The gearing 10, 11 is a two-to-one gearing so that the needle bar will make two reciprocations for each rotation of the shaft 12.

The laterally-movable bearing member 6 through which the lower end of the needle bar 2 passes is received in a housing 80 that is rotatably mounted in the lower end of the head 3, said housing being provided with a hollow stem 90 which is journaled in the lower end of the head 3 and is held in position therein by a lock nut 100. Slidably mounted in the hollow stem 90 is a sleeve 111 which is formed at its lower end with a flange or head 120 that is acted upon by springs 13 within the housing 80, which springs tend to force the head upwardly. This head 120 is provided with a downwardly-extending cam projection 14 which is adapted to engage the inclined face 15 of the bearing block 6 so that downward movement of the cam member 14 will force the block 6 to the right, Fig. 3. The housing 80 is provided with an opening 16 through which the end of the bearing block 6 extends and said bearing block is acted upon by a spring 17 confined within a retainer 78 and which tends normally to move the bearing block to the left Fig. 3. The spring 17, therefore, is the instrumentality which moves the block 6 with the needle bar 2 laterally in one direction when the sleeve 111 and head 120 are elevated, and the cam finger 14 is the instrumentality which moves the block 6 and needle bar 2 laterally in the opposite direction against the action of the spring 17 when the sleeve 111 and head 120 are depressed. The movements of the sleeve 111 and head 120 are controlled by a lever 18 pivoted at 19 to the frame and actuated by a cam 20 on the shaft 12 so that at each rotation of the shaft 12 the sleeve 111 and head 120 will be depressed. Since the needle bar makes two reciprocations at each rotation of the shaft 12, it will follow that at alternate penetrating thrusts of the needle the bearing block 6 and needle bar will be at the right-hand limit of their movement, as shown in Fig. 3, while during the other thrusts of the needle they will be at the left hand limit of their movement, as shown in Fig. 2. This vibrating movement of the needle causes the alternate needle thrusts to be made at the edge of the buttonhole and the other thrusts to be made at a distance back from the edge, all as described in the above-mentioned patent.

Coöperating with the needle are two loopers 21 and 22 with their looper spreaders 23 and 24. These loopers are carried by an oscillating block or carrier 25 which oscillates

about a shaft 26 and is connected by a link 27 with a lever 28 pivoted at 29 to a frame 30 which is rotatably mounted in the bed frame 31 of the sewing machine. The lever 28 is connected by a connection 32 to a spindle 33 which in turn is connected to and actuated by a lever 34 pivoted at 35 and connected by a link 36 to an actuating lever 37 which is actuated by a cam 38 on the shaft 12. This mechanism serves to vibrate or oscillate the block or carrier 25, thus bringing the loopers 21, 22 alternately into position to enter the loops of needle thread, each looper when it enters its loop of needle thread coöperating with its looper spreader 23 to spread the loop and carry it into a position to be entered by the needle on the next thrust thereof. For a more full and complete description of the above-mentioned parts reference may be had to said Patent No. 862,238.

The concatenation of the needle thread loops resulting from the above-described mechanism is shown somewhat diagrammatically in Figs. 7 and 8 from which it will be seen that the alternate thrusts of the needle pass a loop of needle thread 39 from one side to the other of the fabric at or adjacent the edge 40 of the buttonhole, while on other thrusts of the needle a loop of needle thread 41 is passed through the goods at a distance back from the edge 40. The Jooper mechanism takes each loop of needle thread and positions it so that the next succeeding loop is passed therethrough and thus the bights 42 of the needle thread loops which engage the next succeeding loop are all situated on the under side of the fabric, these bights of the loops giving to the stitch a purl effect on said under side of the fabric. On the upper side of the fabric will appear the portions 45 of the needle thread which connect the successive loops.

In order to give a so-called purl appearance to the stitch on the upper side of the fabric, I have provided means for concatenating a purl thread 44 with the portions 45 of the needle thread, this purl thread being twisted once about each of the portions 45 of the needle thread. This end is secured by means of a purl thread guide 43 which is associated with the needle bar 2 and is operated to lay the purl thread 44 so that at each penetrating thrust of the needle the portion 45 of the needle thread will be laid over the purl thread.

In the illustrated embodiment of the invention this purl thread guide 43 is provided with thread-guiding apertures through which the purl thread 44 extends and is pivotally connected to the housing 80 by means of a pivotal stud 46. This guide 43 is given its vibrating movement to position properly the purl thread at each stitch by the needle-bar-vibrating mechanism, so that

the vibrating movement of the purl thread guide 43 is in timed relation with that of the needle bar. While various devices for accomplishing this may be provided, I 5 have herein shown a simple construction which includes a projection or finger 47 extending from the upper end of the guide 43 and in position to be engaged by a laterally-extending projection 48 secured to the head 10 of 120, said projection operating through a slot 49 in the housing 80. The purl thread guide 43 is acted upon by a spring 50 which tends to swing it into the position shown in Fig. 2, said spring being connected at one end 15 to a pin 51 extending from the guide and being connected at the other end to a pin 52 secured to the housing 80. With this construction it will be seen that at each downward movement of the sleeve 111 and head 20 120 the purl thread guide 43 will be moved to the right into the position shown in Fig. 3 by the engagement of the projection 48 with the finger 47, and during this same time the needle bar 2 will be moved to the 25 right. When the sleeve 111 is elevated the spring 50 will throw the purl thread guide to the left into the position shown in Fig. 2 and the spring 17 will move the needle bar 2 to the left. The purl thread guide is so 30 situated that at each thrust of the needle the needle will pass back of the purl thread as shown in Figs. 7 and 8, which illustrates quite nearly the operation of the guide 43 in laying the purl thread. Fig. 7 shows the 35 needle 1 making its penetrating thrust at the edge 40 of the fabric, the needle at this time being in a position illustrated in Fig. 3. At the same time the guide 43 is carried into its right hand position beyond the 40 needle 1 and the purl thread 44 is so positioned that the needle will pass back thereof and will lay the portion 45 of the needle thread over the purl thread. As the needle is elevated the purl thread guide 43 is swung 45 to the left into the position shown in Figs. 2 and 8, thus carrying the purl thread over the portion 45 of the needle thread which has just been laid, and when the needle makes its next thrust, as shown in Fig. 8, it 50 will pass back of the purl thread and will lay the portion 45^a of needle thread over the purl thread. When the needle is elevated again the purl thread guide 43 moves back into the position shown in Fig. 7, thus carrying 55 the purl thread over the portion 45^a of needle thread and in position to have the needle thread laid over it at the next penetrating thrust of the needle. The result is that the purl thread will be twisted about the portions 45 of needle thread, and when 60 the purl thread is drawn tight, it will give a purl appearance to the buttonhole stitch on the upper side of the fabric.

In the sewing machine herein illustrated 65 the looper 21 is constructed to carry a looper

thread 60 which is concatenated with the loops of needle thread on the under side of the goods to augment the purl appearance of the buttonhole stitch on said side of the goods, all as described in the above-mentioned Patent No. 862,238. It will thus be seen that this invention provides for making a buttonhole stitch which has a purl effect on both sides of the goods, and while I have illustrated one embodiment of the 75 invention and the invention as applied to one type of sewing machine, I do not wish to be limited to the constructional features shown.

I claim:

1. In a buttonhole sewing machine, the combination with a frame having a head, of a reciprocating needle bar mounted in said head, means to reciprocate said needle bar, a laterally-shiftable element mounted in 85 said head and through which the needle bar extends, a vertically-movable sleeve mounted in said head and having provision for moving said laterally-shiftable element laterally, a vibratable purl thread guide mounted on the head, and means to actuate said guide by movement of said sleeve.

2. In a buttonhole sewing machine, the combination with a needle and its needle bar, of means to reciprocate said needle, a laterally-shiftable bearing member through 95 which the needle bar extends, an actuating member movable in a direction parallel to the reciprocations of the needle bar for giving lateral movement to said bearing member, a vibratory purl thread guide, and means to actuate said guide by the movement of the actuating member.

3. In a buttonhole sewing machine, the combination with a frame having a head, 105 of a needle bar mounted for reciprocation in said head, a bearing member slidably mounted laterally in said head and through which the needle bar extends, an actuating member mounted in said head for vertical reciprocating movement, means to give lateral movement to the bearing member by movement of said actuating member, and a purl thread guide pivoted to said head and actuated by said actuating member.

4. In a buttonhole sewing machine, the combination with a needle and its needle bar, of means to reciprocate the needle bar, a laterally-shiftable bearing member through which the needle bar extends, a spring acting on said bearing member and tending to move it in one direction, an actuating member movable in a direction parallel to the reciprocations of the needle bar for giving lateral movement to said bearing member in the opposite direction, a vibratory purl thread guide, and means to actuate said guide by the movement of the actuating member.

5. In a buttonhole sewing machine, the 130

combination with a needle and its needle bar, of means to reciprocate said needle bar, a laterally-shiftable bearing member through which the needle bar extends, an actuating member movable in a direction parallel to the reciprocations of the needle bar for giving lateral movement to said bearing member, a vibratory purl thread guide, a spring

acting on said guide and tending to move it in one direction, and means to move said guide in the opposite direction by movement of the actuating member.

In testimony whereof, I have signed my name to this specification.

FRANK SALVATO.
